CLAIM

The ornamental design for a hat, as shown and described.

DESCRIPTION

The file of this patent contains at least one drawing executed in color. Copies of this patent with color drawing(s) will be provided by the Office upon request and payment of the necessary fee.

FIG. 1 is a front, left perspective view of the first embodiment for a hat, showing my new design;

FIG. 2 is a front, left perspective view of the second embodiment for a hat;

FIG. 3 is a front, left perspective view of the third embodiment for a hat; and,

FIG. 4 is a front, left perspective view of the fourth embodiment for a hat.

The broken lines portion of the figure drawings show portions of the article and form no part of the claimed design.

**1 Claim, 4 Drawing Sheets
(2 of 4 Drawing Sheet(s) Filed in Color)**
